UNITED STATES PATENT OFFICE

2,202,735

CORROSION RESISTANT VALVE

John S. Johnson, Scranton, Pa.

Application December 30, 1938, Serial No. 248,592

3 Claims. (Cl. 251—158)

The present invention relates to valves and particularly to gate valves for use in distribution systems carrying considerable volumes of water or other fluids. More particularly, the present invention is directed to corrosion resistant valves for use in connection with chemical apparatus, or systems carrying acids or acidulated liquids, and has for its principal object the provision of a valve of the character described, which is so constructed and arranged as to suffer a minimum of damage from corrosion due to contact with acid solutions.

It is common practice in chemical plants, and in other applications in which acid solutions are involved, to employ valves made of corrosion resistant metals, such as special chemically resistant bronzes and the like. However, it is the fact that few if any non-precious metals are proof against corrosion by acids, even though certain metals and alloys have greater resistance to corrosion than others. Moreover, such corrosion resistant materials are relatively expensive and in certain applications involving the use of considerable numbers of large, rugged valves, the expense of using valves constructed wholly of corrosion resistant metals is considerable. One such application is found in coal mining operations, which involve the handling of large quantities of water, not only in the treatment of the coal, as in the breakers, separators, etc., but in the removal of water from the mines, etc.

It is well known that the water which is pumped from coal mines contains sulfuric acid in solution, and in fact, most of the water available for use on a large scale in coal mining regions is definitely acid. If valves made of ordinary materials are employed in handling such waters, the valves soon become corroded to such an extent as to impair their operation, and likewise require relatively frequent replacement.

The quantity of acid to which a metal part is subjected, and hence the degree of corrosion resulting therefrom, is proportional to the quantity of acidulated liquid passing such part, and hence it is important to prevent the circulation of the acidulated water or other liquid past the operating parts of the valve, although relatively little damage will be done by permitting a quiescent body of an acid solution to remain in contact with such parts, when such solution is comparatively dilute.

In view of the foregoing, it is an object of the present invention to provide a valve operating in a chamber which is separated from the conduit in such a manner as to prevent the circulation of the liquid past or in contact with the operating parts of the valve.

Another object is the provision of a valve of the character described, in which those parts of the valve member and valve body which are

subjected to the passing liquid are provided with a lining or covering of acid resistant material, such as rubber.

Other and further objects, features and advantages of the present invention will be apparent to one skilled in the art from the following description taken in connection with the accompanying drawing, in which:

Figure 1 is a vertical section on a valve constructed in accordance with the present invention; and

Figure 2 is a section on line 2—2 of Figure 1.

In order to facilitate an understanding of the invention, reference is made to the embodiment thereof shown in the accompanying drawing and detailed descriptive language is employed. It will nevertheless be understood that no limitation of the invention is thereby intended and that various changes and alterations are contemplated such as would ordinarily occur to one skilled in the art to which the invention relates.

The valve of the present invention comprises generally a valve body 6, a valve member 20, and mechanism for operating the latter. The valve body 6 comprises an outer casing 8, of metal or other suitable material, and an inner lining 9 of vulcanized rubber or other corrosion resistant material. The valve body is formed to provide an L-shaped fluid passage therethrough, such passage comprising a horizontal branch 10 and a vertical branch 11. The valve body is provided, adjacent the extremities of the respective branches 10 and 11, with flanges 12 and 13, respectively, for connecting the valve in a fluid distribution system, and it will be noted that the lining 9 overlies the outer surfaces of the flanges 12 and 13, thus providing an integral gasket for sealing the joints between the valve body and the adjacent conduit sections. The valve body is formed with a valve chamber 14 in axial alignment with one branch of the fluid passage, namely the branch 11 in the illustrated embodiment. The branch 11 of the fluid passage is provided with an inwardly projecting inclined shoulder forming a valve seat 15, and the chamber 14, near its juncture with the fluid passage, is likewise formed with an inwardly projecting inclined shoulder forming a second valve seat 16. It will be noted that the rubber lining 9 extends throughout the chamber 14 as well as throughout the branches 10 and 11 of the fluid passage. The upper end of the chamber 14 is closed by a cover plate 17, which may be bolted or otherwise suitably secured to the adjacent flange 18 of the casing 8, a portion of the rubber lining 9 overlying the latter flange. In addition, the cover plate 17 is provided with a similar lining 19, the peripheral portion of which is clamped between the cover plate 17 and the flange 18. The valve mem-

ber 20, which is reciprocably mounted in the valve chamber 14, comprises a cylindrical metal casting 21 and a covering 22 of rubber or similar corrosion resistant material, and is formed with an outwardly and upwardly projecting flange 23 at its upper end, the lateral surface 24 of said flange being adapted to make a fairly tight sliding fit with the inner surface of the wall of said chamber. The lower inclined surface 25 of the flange 23 constitutes a seating surface for engagement with the valve seat 16, while the peripheral portion of the lower surface 26 of the valve member 20 is adapted to simultaneously engage the valve seat 15 in the branch 11 of the fluid passage. The outer diameter of the valve member 20, below the flange 23, corresponds to the inner diameter of the cylindrical wall 27 connecting the chamber 14 and the fluid passage so that the valve member makes a fairly tight sliding fit therewith.

A valve stem 28 is threaded into the upper end of the valve member 20, and is locked in place by means of a set screw 29. The stem 28 extending outwardly through the cover plate 19 is threaded throughout a major portion of its length for engagement with the internally threaded lifting nut 30, which is secured against outward displacement by means of the shouldered sleeve 31, the latter being bolted or otherwise suitably secured to the cover plate 17. A hand wheel 32 is rigidly secured to the lifting nut 30 for rotating the latter, the downward thrust of the lifting nut being taken by a washer 33 positioned in a suitable recess in the upper face of the cover plate 17. The valve stem 28 is keyed to the cover plate 17 by means of a key 34, to prevent rotation of the stem 28 and valve member 20. From the foregoing, it will be obvious that the valve member 20 may be reciprocated into and out of engagement with the seats 15 and 16 by turning the hand wheel 32 and lifting nut 30. The chamber 14 is sufficiently long to accommodate the valve member 21 in its entirety, so that the latter may be entirely withdrawn from the valve passage so as not to obstruct the same in any way.

When the valve member 20 is in the position illustrated, it will be apparent that the chamber 14 is sealed from the fluid passage 10, 11 not only by the engagement between the surface 25 and the seat 16 but also by the engagement of the surface 24 with the lining 9 of the chamber and the engagement of the cylindrical wall of the valve member with the surface 27 of the chamber. Thus, in effect, there is a triple seal preventing the penetration of liquid from the passage 10, 11 into the chamber 14. When the valve is lifted to open the passage 10, 11, the seal between the surface 25 of the valve member and the valve seat 16 is broken, but the wall of the valve member continues to engage the surface 27 of the chamber and the lateral surfaces 24 of the flange 23 continues to engage the inner surface of the main portion of the chamber, thus providing a double seal against the penetration of liquid into the chamber. Such liquid as may seep into the chamber during the course of time will remain quiescent therein, and will have little corrosive effect upon the valve stem 28. The latter will preferably be made of corrosion resisting metal, but it is obvious that the remaining parts of the assembly may be made of ordinary metals or other suitable materials, since they do

not come in contact with the liquid standing in the chamber 14. Obviously, when the valve is open, no metal part is in contact with the liquid flowing through the passage 10, 11.

When the valve member 21 is fully retracted, the upper annular surface 35 of the flange 23 is adapted to engage the upper inner surface 19 of the valve chamber, thus effecting an additional seal between the fluid passage and the valve stem. The valve is thus self-packed, or in other words, if the valve, when opened, is fully retracted, the seal between the surface 35 and the surface 19 will prevent any leakage of fluid past the stem 28, and the usual valve stem packing may be dispensed with.

Having thus described the invention, what is claimed as new and desired to be secured by Letters Patent is:

1. In a corrosion resistant valve, a valve body having an L-shaped passage and a valve chamber communicating therewith and in alignment with one branch of said passage, said branch of said passage and said valve chamber being provided with inwardly projecting peripheral seat portions, a valve member reciprocably mounted in said chamber and adapted to project into said passage, said valve member having a cylindrical surface adjacent one end thereof adapted to slidably engage the inner wall of said chamber, a seating surface adjacent said cylindrical surface adapted to engage said seat portion of said chamber, and a seating surface at the opposite end thereof adapted to engage said seat portion of said passage, said passage and chamber having an inner lining of corrosion resistant material and said valve member having an outer covering of corrosion resistant material, and means for reciprocating said valve member longitudinally of said chamber into and out of engagement with said seats, said valve member having a relatively tight sliding engagement with a portion of the wall of said chamber adjacent said passage, whereby a double seal is effected between said passage and the outer end of said chamber.

2. In a corrosion resistant valve, a valve body having a passage therethrough and having a valve chamber communicating with said passage, said valve body being formed with an inwardly projecting peripheral seat in said passage and a second inwardly projecting peripheral seat in said chamber, a valve member reciprocably mounted in said chamber and adapted to project into a portion of said passage, said valve member having a cylindrical surface adapted to slidably engage the inner wall of said chamber, seating surfaces adapted simultaneously to engage said seats in said passage and said chamber, respectively, and a raised annular surface on the upper end of said member adapted to seat on and effect a seal with the upper inner surface of said chamber, and means for reciprocating said valve member longitudinally of said chamber into and out of engagement with said seats and said upper inner surface of said chamber, whereby a seal is effected between said raised annular surface and said upper inner surface of said chamber when the valve is in fully open position.

3. A valve assembly as defined in claim 2, said raised annular surface of said valve member and said upper inner surface of said chamber consisting of corrosion resistant material.

JOHN S. JOHNSON.
